UNITED STATES PATENT OFFICE.

EMIL CARL ZIMMERMAN, OF NEW YORK, N. Y., ASSIGNOR TO Q & C COMPANY, OF NEW YORK, N. Y., A CORPORATION OF MAINE.

SPLICE BAR FOR RAIL JOINTS.

Application filed December 9, 1927. Serial No. 238,757.

This invention relates to improvements in splice bars for rail joints and consists in a novel structural formation of the bar which admits of an improved and more effective distribution of the metal to obtain materially added strength and stiffness of the bar structure for a given cross sectional area and weight of metal.

The present invention primarily has in view the production of a rail joint bar which may be economically produced by standard rolling practice, including structural modification which permits of a substantial lightening of the section while possessing a more effective distribution of the metal to allow of a saving in cross sectional area without materially diminishing or reducing the stiffness and strength of the resulting bar.

In the improved modification of the bar structure the features of the present invention are further preferably embodied so as to preserve the standard bearing surfaces for fishing engagement with the under side of the rail head and with the rail base flange and further to preserve the outer vertical plane surface of the web portion to be properly engaged by the bolt heads or nuts of the usual fastening devices.

To this end my improved splice bars are of a novel form conforming generally to standard cross sectional contour but wherein their non-bearing surfaces are formed alternately of longitudinally extending ribs and grooves of suitable size or proportion to determine a substantial cross-section or thickness of the members thereof, while employing a minimum cross sectional area and weight of metal therefor.

In further accordance with the present invention where the improved rib and groove formation is applied on opposite sides of a portion of a member of the bar, they are arranged whereby a rib will be opposite to a corresponding groove so as to avoid undue reduction of the section. The provision of the enlarged rib and curved surface upon the bar members, as herein contemplated, allows of obtaining a materially improved bar structure with respect to a more effective distribution of the metal which may be economically produced in the rolling operation without offering any particular or difficult problem as to flow of metal and excessive deformation and as will be further appreci-

ated, avoids the necessity of geared rolls in its production. 55

The described and other features and advantages of my improved spliced bar structure will be more readily understood by reference to the accompanying drawings wherein like reference numerals are applied to the corresponding parts in the several views. 60

In the drawings

Fig. 1 is a perspective view showing my improved splice bar structure employed in a 65 rail joint;

Fig. 2 is a view thereof in vertical cross section;

Fig. 3 is a cross-sectional view of a modified form. 70

In the approved and practical embodiment of the features of my invention as herein shown, the splice bar comprises the usual web portion 1, head portion 2 and base flange portion 3, conforming in general to the standard angle bar structure provided with the usual inclined head fishing surface 4 engaging the under side of the rail head 5 and the inclined base fishing surface 6 engaging the upper surface of the rail portion 7. 80

In accordance with my present invention, the bar is modified in its structural form by the provision of longitudinally extending surface ribs 8 and grooves 9, of suitable size to effect a substantially improved distribution of the metal so as to obtain high values in stiffening and strengthening of the bar wall with a minimum metal requirement. The ribs and grooves may desirably be of reverse curvature in cross sectional contour, 85 as illustrated, and of substantially corresponding size. In further accordance with the preferred form of my invention, the modified rib and groove formation of the bar may be embodied so as to occur upon the major 90 surfaces of the bar other than the bearing surfaces thereof. In accordance therewith, as here illustrated, the rib and groove deformations are incorporated with the outer non-bearing surface of the head portion 2, the 100 inwardly directed surface of the web portion, the upper surface of the splice bar flange and the under surface of the flange member projecting beyond the rail base. The fishing surfaces of the angle bar and the vertical outer surface of the web portion are of the conventional form having plane and unaltered surfaces. As will be noted, the ar- 105

angement of the ribs and grooves, or enlarged corrugation, of the bar flange portion at its outer end is such that the ribs of one surface are opposite to the grooves of the other surface, so as to produce a substantial uniform thickness at this portion.

In the manufacture of a joint bar embodying the improved features of the present invention, the simple alteration of the surface 10 form may be readily effected in the rolling operation, from which it results that the bar is susceptible of economical production and results in a bar affording material improvements as to economical distribution of metal 15 employed.

As will be readily understood, the primary feature of the invention is necessarily susceptible of application to various shapes and types of joint bars, and further susceptible 20 of modification as to the extent of its use upon the respective surfaces of the bar, but as herein disclosed in its preferred form, is embodied with the major portion of the non-bearing surfaces of the bar so as to obtain 25 the maximum values therefrom, while preserving the conventional portions of the bar unaltered so as to be fully and properly effective for their desired purposes.

In Fig. 3 there is illustrated a suitably 30 modified form of the improved splice bar wherein the outer face of the web portion is provided with upper and lower longitudinally extending shoulders 10, 11 having a concaved or grooved portion therebetween. 35 As shown, said shoulders 10 and 11 are spaced to be engaged by the washers 12 at the outer edges thereof whereby upon tightening of the usual securing nut 13 the washers are subjected to a distortion or deflection contribut- 40 ing to the securing value thereof.

Having described my invention, I claim:

1. A splice bar for rail joints having its bearing portions of standard contour with plane surfaces and having non-bearing portions formed with a series of alternate, longitudinally extending rib and groove surfaces, substantially as described.
2. A splice bar for rail joints of uniform section having its bearing portions of standard contour with plane surfaces and having non-bearing portions formed with a series of alternate, longitudinally extending rib and groove surfaces, said ribs and grooves being of curvilinear cross-sectional contour.
3. A splice bar for rail joints of uniform section having its bearing portions of standard contour with plane surfaces and having its major non-bearing surfaces of contiguous, longitudinally extending rib and groove formation.

4. A splice bar for rail joints of uniform section having its bearing portions of standard contour with plane surfaces, said bar being of angle type and formed with the outer head portion and upper flange portion having surface deformations providing a series of longitudinally extending ribs and grooves. 65

5. A splice bar for rail joints of uniform section having its fishing portions of standard contour with plane surfaces, said bar being of angle type and formed with the outer head portion, vertical, inner web portion and upper flange portion having surface deformation providing a series of longitudinally extending ribs and grooves of substantial dimensions. 70

6. A splice bar for rail joints of uniform section having its fishing portions of standard contour with plane surfaces, said bar being of angle type and formed with the outer head portion, inner web portion, upper flange portion and outermost lower flange portion provided with surface deformations providing longitudinally extending ribs and grooves, said ribs and grooves being of substantial dimensions having a curvilinear surface contour. 80

7. A splice bar for rail joints of uniform section having its bearing portions of standard contour with plane surfaces and having 90 its major non-bearing surfaces of contiguous, longitudinally extending rib and groove formation, said ribs and grooves being of substantial dimensions and having a curvilinear surface contour. 95

8. A splice bar for rail joints of uniform section having its fishing surfaces of standard contour, said bar being of angle type and formed with the inner web portion, upper flange portion and outermost lower flange 100 portion provided with surface deformations providing longitudinally extending grooves and ribs, said flange deformations being arranged whereby the ribs of one surface are opposite the grooves of the other surface, substantially as described. 105

9. A splice bar for rail joints of uniform section having a vertical web portion having its outer surface formed with upper and lower shoulders longitudinally extending thereof, said shoulders being spaced to be engaged by the extreme edge portions of the usual spring washers and having a concaved or groove portion intermediate of the shoulders, substantially as described. 110

Signed at New York city, in the county of New York and State of New York, this 28th day of October A. D. 1927.

EMIL CARL ZIMMERMAN.
